UNITED STATES PATENT OFFICE.

FRANK KARSCHITZ, OF BRIDGEPORT, CONNECTICUT.

TOY SWING-CHAIR AND SULKY.

1,343,000.

Specification of Letters Patent.

Patented June 8, 1920.

Application filed January 5, 1920. Serial No. 349,521.

To all whom it may concern:

Be it known that I, FRANK KARSCHITZ, a citizen of the Republic of Hungary, residing at 726 Pembroke St., Bridgeport, county of 5 Fairfield, State of Connecticut, have invented an Improvement in Toy Swing-Chairs and Sulkies, of which the following is a specification.

The object of the present invention is to 10 provide a novel toy adapted to be used either as a sulky or a swinging chair, which will be extremely simple in construction, cheap to manufacture, and attractive in appearance.

15 With the above and other objects in view, the invention comprises the construction and arrangement of parts as now to be described and hereinafter specifically claimed.

In the drawing forming a part of this 20 specification,

Figure 1 is a perspective view showing the sulky used in connection with a stand as a swinging chair;

Fig. 2 a side elevation showing the sulky 25 detached from the stand;

Fig. 3 a perspective view of the removable tongue for the sulky; and

Fig. 4 is a sectional view showing in detail the detachable connection between the 30 tongue and the foot rest of the sulky.

The stand comprises parallel uprights 10 which are connected at the top by a cross rod 11 and are strengthened by braces 12.

The sulky is provided with a back 13, a 35 seat 14, and a foot rest 15. The opposite sides of the seat are bent downwardly at right angles as indicated at 16 and to the downwardly bent portions are attached strips 17 of material. The downwardly bent

40 portions are extended, as indicated at 18, and have therein perforations 19 for an axle 20 carrying wheels 21. The opposite sides of the back are bent backwardly at right angles, as indicated at 22, and each backwardly bent portion is attached to a strip 23 of material. The foot rest is connected to the back by strips of material bent as shown. The upper ends of these strips are secured to the 45 opposite sides of the back, as indicated at 24, the strips are bent forwardly at right angles to produce the arms 25, downwardly at right angles to produce supporting strips 26, and again forwardly at right angles to 50 produce attaching portions 27 for the foot

rest. At points intermediate their ends the 55 supporting strips are attached to the front ends of strips 17 of material, as indicated at 28, and near their rear ends, strips 17 are attached to strips 23 of material, as indicated at 29. Extensions 30 of strips 17 are provided to rest the sulky in a tilted back position and to prevent it from turning over 60 backward.

Each of the arms of the sulky is provided with a plate, indicated at 31, and through 65 each plate is a rectangular opening 32. On each of strips 17 of material and directly below each rectangular opening, is a headed pin 33. The cross rod for the uprights pivotally carries hanger straps 34 which are 70 provided with offset portions 35 near their upper ends. The lower ends of the hanger straps are provided with fastening slots, as indicated at 36, and a flat strip 37 of material has its opposite ends attached to the 75 offset portions to insure the locations of the hanger straps.

A table 38 is provided at its opposite sides with strips 39 of material, and the inner end of each of these strips is bent downwardly 80 at right angles. One of these downwardly bent portions is pivotally attached to a supporting strip adjacent its upper end, as indicated at 40, so that the table may be swung upwardly and downwardly on the pivot, 85 and the other downwardly bent portion has therein a U-shaped slot 41. Adjacent the upper end of the other supporting strip is a headed pin 42 on which the upper wall of the U-shaped slot is adapted to rest when 90 the table is swung to its horizontal position and across the front of the sulky, as will be readily understood.

The removable tongue 43 is provided with a rest 44 and an offset lower portion 45. In 95 the offset lower portion is a fastening slot 46 and a perforation 47. Attached to the foot rest adjacent its front edge and intermediate its sides, is a shaped plate 48 which provides a rectangular opening 49 between 100 the foot rest and the shaped plate. The shaped plate is provided with a perforation 50 in which is permanently arranged for upward and downward sliding, a locking pin 51 carrying on its upper end a knob 52 105 and on its lower end a head 53, both of a size to prevent their passage through the perforation. In the foot rest and directly

below perforation 50 is a perforation 54 of slightly larger size which allows passage of head 53. Adjacent the rear edge of the foot rest and in alinement with opening 49 is a headed pin 55 for a purpose to be explained.

The novel sulky may be used in connection with the stand as a swinging chair, as disclosed in Fig. 1, or it may be used without the stand, as disclosed in Fig. 2. In 10 both instances the manipulation of the table is the same. When it is desired to place a doll in the sulky one end of the table is swung up, as is suggested in Fig. 1, and after the doll is seated, that end of the table 15 is swung down until the upper wall of the slot engages the pin.

To attach the sulky to the stand, the hanger straps are passed through the rectangular openings in the plates and the 20 lower ends of the hanger straps are sprung outwardly to allow the heads of the pins to pass through the enlarged parts of the fastening slots. The lower ends are then released and the sulky is allowed to carry the 25 headed pins to the bottoms of the fastening slots. The heads on the pins will insure a reliable connection. To remove the sulky the operation is reversed.

By means of flat strip 37 the upper ends 30 of the hanger straps are held close to the upper portions of the parallel uprights and lateral movement of the sulky, when in use as a swinging chair, is prevented. The offset portions provide space between the hanger straps and the uprights, so that there 35 is no interference between the swinging chair and the stand.

When the novel toy is in use as a swinging chair, the removable tongue is detached. 40 To attach the tongue to the sulky, as it is disclosed in Fig. 2, the fastening pin is raised to the position shown in Fig. 4, and the offset lower portion of the tongue is inserted in the opening between the shaped 45 plate and the foot rest. With the tongue tilted slightly downward, the enlarged part of the fastening slot is positioned over the headed pin. The tongue is then elevated until the headed pin passes through said 50 enlarged part of the fastening slot, and is then pulled slightly forward until the outer end of the reduced wall of the fastening slot engages the headed pin. This will align perforations 47 and 54 so that the fastening pin 55 will drop therethrough. It will be apparent that the fastening pin will hold the outer end of the reduced wall of the fastening slot against the headed pin, and thus effect a reliable connection between the tongue and the 60 sulky. To detach the tongue the operation is reversed.

What I desire to claim is:

1. A toy swing chair and sulky of the character described, comprising a sulky having 65 a tongue, a stand having uprights piv-

otally carrying hanger straps, and means for disengageably connecting said sulky to said tongue and to said hanger straps.

2. A toy swing chair and sulky of the character described, comprising a sulky provided with a tongue, a stand having uprights provided with a cross rod pivotally carrying hanger straps, means for disengageably connecting said sulky to said tongue, and other means for disengageably connecting said sulky to said hanger straps. 70 75

3. A toy swing chair and sulky of the character described, comprising a sulky provided with a tongue, a stand having uprights provided with a cross rod pivotally carrying hanger straps having offset portions, means for disengageably connecting said sulky to said tongue, and other means for disengageably connecting said sulky to said hanger straps, whereby when the sulky 80 85 is disconnected from the hanger straps it may be operated by said tongue, and when connected to said hanger straps it may be used as a swinging chair.

4. A toy swing chair and sulky of the character described, comprising a sulky having side arms carrying plates provided with openings, a seat carrying strips having headed pins thereon in alinement with said openings, and a foot rest provided with means 95 for attaching it to a tongue, in combination with a stand having uprights and a cross pin connecting the uprights and pivotally carrying hanger straps, the hanger straps being adapted to pass through said openings 100 and to have disengageable connection with the headed pins, and a tongue carrying at its lower end means for attaching it to said foot rest.

5. A toy swing chair and sulky of the character described, comprising a sulky having side arms carrying plates provided with rectangular openings, a seat carrying strips with headed pins thereon in alinement with said openings, and a foot rest provided with an opening and a headed pin in alinement therewith, in combination with a stand having uprights and a cross pin connecting the uprights and pivotally carrying hanger straps, the hanger straps being adapted to 105 pass through said rectangular openings and to have disengageable connection with the headed pins, and a tongue adapted to be inserted through the opening of the foot rest and having means for disengageably connecting it with the headed pin thereon. 110 115 120

6. A toy swing chair and sulky of the character described, comprising a sulky having side arms carrying plates provided with rectangular openings, a seat carrying strips with headed pins thereon in alinement with said openings, and a foot rest provided with an opening and a headed pin in alinement therewith, in combination with a stand having uprights and a cross rod connecting the 125 130

- uprights and pivotally carrying fixedly located hanger straps having offset portions, the hanger straps being adapted to pass through said rectangular openings and to have disengageable connection with the headed pins, and a tongue adapted to be inserted through the opening of the foot rest and having means for disengageably connecting it with the headed pin thereon.
7. A toy swing chair and sulky of the character described, comprising a sulky carrying plates provided with rectangular openings, and carrying headed pins directly beneath said plates and in alinement with said openings, and having attached thereto a foot rest, in combination with a stand having hanger straps pivotally swung therefrom, the said hanger straps being adapted to pass through the rectangular openings and to have disengageable connection with the headed pins, and a tongue adapted to have disengageable connection with the foot rest.
8. A toy swing chair and sulky of the character described, comprising a stand, a sulky, and a tongue for said sulky, said stand and said sulky being adapted for disengageable connection by means of pivoted hanger straps on said stand and headed pins on said sulky, and said sulky and said tongue being adapted for disengageable connection by means of a headed pin and a fastening pin on said sulky and a fastening slot and a perforation in said tongue.
9. A toy swing chair and sulky of the character described, comprising a sulky provided with a foot rest and a tongue attached thereto, a stand having uprights provided with a cross rod pivotally carrying hanger straps, means for disengageably connecting said sulky to said tongue, and other means for disengageably connecting said sulky to said hanger straps.
10. A toy sulky of the character described, comprising a back, a seat having integral downwardly bent side portions carrying wheels, a foot rest, angularly bent strips of material connecting said back and foot rest and providing side arms, and a tongue, said foot rest and tongue being adapted for disengageable connection with each other.
11. A toy sulky of the character described, comprising a back, a seat having integral downwardly bent side portions carrying wheels, a foot rest, angularly bent strips of material connecting said back and foot rest and providing side arms, and a tongue, said foot rest and tongue each carrying means adapting them to be disengageably connected with each other.
12. A toy sulky of the character described, comprising a sulky provided with a pivoted table and a foot rest, said pivoted table being arranged to extend horizontally across the front of said sulky or to be swung upwardly from horizontal position, and said foot rest being provided with means for detachably connecting thereto a tongue.
13. A toy sulky of the character described, comprising a sulky, provided with a foot rest and a tongue, said foot rest having therein adjacent its front edge and intermediate its ends, a perforation, and carrying directly above said perforation, a shaped plate providing a rectangular opening between said foot rest and said shaped plate, and carrying adjacent its rear end and in alinement with said rectangular opening, a headed pin, and said shaped plate slidably carrying a fastening pin, and said tongue having therein a fastening slot and a perforation, whereby when said tongue and foot rest are connected, a wall of said fastening slot will engage said headed pin and said fastening pin will drop through said perforations in said foot rest and said tongue.

In testimony whereof I affix my signature.

FRANK KARSCHITZ.
